UNITED STATES PATENT OFFICE.

JOHN OSTER, JR., OF NEWPORT, KENTUCKY.

PIANO-HAMMER.

SPECIFICATION forming part of Letters Patent No. 622,065, dated March 28, 1899.

Application filed March 2, 1898. Serial No. 672,284. (No model.)

To all whom it may concern:

Be it known that I, JOHN OSTER, Jr., of Newport, in the county of Campbell and State of Kentucky, have invented a new and useful 5 Improvement in Piano-Hammers, of which the following is a specification.

My invention relates to that form of piano-hammer in which the striking-surface is made in the form of a rotatable disk of felt, which 10 may be adjusted about its axis so as to allow a new peripheral surface to be brought around to striking contact whenever one portion of said surface shall have become flattened and hard from long use.

15 My invention consists in the special construction and arrangement of parts, which I will now proceed to describe with reference to the drawings, in which—

Figure 1 is a side view of the hammer; Fig. 20 2, a longitudinal section; Fig. 3, a transverse section through the felt disk, and Fig. 4 an assemblage of the various parts detached from each other.

In the drawings, A represents the holder for 25 the felt disk C. This holder consists of a tapered stem or shank portion having screw-threaded end a^2 and two divergent spring arms or jaws a , which at their ends are curved to snugly fit the periphery of the felt 30 disk and embrace a little more than one-half of its circumference. The spring-jaws a have along their inner edges inturned flanges a' , which flanges when the jaws are gripped upon the felt disk bury into the felt (see Fig. 35) and prevent the felt disk from slipping out sidewise from between the jaws. These jaws, including the flanges, are exactly the same thickness as the disk, so that they lie flush with the felt, and there is no projection on the 40 sides of the disks and no liability for one hammer to catch into or interfere with the hammers adjacent thereto. The tapered shank portion of the holder A is received into a tapered socket B, having a right-angularly-extended ferrule b , and said holder is secured within said socket by a nut D, screwed upon the threaded stem a^2 outside of the socket B. By turning this nut up more or less tightly

the holder A is drawn down in the socket and the jaws compressed upon the felt disk to securely hold it in place. The thimble b of the socket B is secured upon the wooden hammer-staff by screw b' or by any other suitable means.

The parts A B D may be made of any material; but I prefer some light and strong material, such as aluminium, hard rubber, vulcanized fiber, &c.

With this construction of hammer it will be seen that when any portion of the felt disk becomes hard and compact from continued and frequent impact it may be quickly loosened and turned. There are, furthermore, no projecting parts on the side of the disk to cause interference between the hammers or 65 objectionable noise in playing. By the swiveling character of the holder A in its socket B before being tightened it is possible also to adjust the plane of the disk C at any angle to the plane of the hammer-staff to better adjust 70 it to striking contact with the wires.

I do not claim, broadly, a rotatable felt disk; but,

Having thus described my invention, what I claim as new, and desire to secure by Letters 75 Patent, is—

1. A piano-hammer comprising an elastic striking-cushion, an elongated socket, a cushion-holder arranged therein and means for positively locking the holder, at an angle to 80 the staff, with a swiveling adjustment substantially as shown and described.

2. A piano-hammer comprising a rotatable elastic disk, spring clamping-jaws for grasping the same peripherally, a socket-holder receiving and embracing the jaws, and means for holding and locking the jaws down in the socket to produce a gripping strain on the elastic disk, substantially as and for the purpose described.

3. A piano-hammer comprising a rotatable elastic disk, a pair of spring clamping-jaws for grasping the same peripherally, said jaws having a screw-threaded shank, a tapering socket receiving said jaws and provided with a staff-ferrule, and a nut arranged upon the

threaded shank and drawing down and compressing the jaws in the socket, substantially as and for the purpose described.

4. A piano-hammer comprising a rotatable elastic disk, and a pair of spring clamping-jaws having along their inner edges inturned flanges sunk into the disk and grasping the disk peripherally, said jaws and flanges be-

ing the same width as the thickness of the elastic disk substantially as and for the purpose described.

JOHN OSTER, JR.
